LATCH

Donald W. Harling, Milwaukee, Wis., assignor to McGraw-Edison Company, a corporation of Delaware

Application May 11, 1955, Serial No. 507,612

7 Claims. (Cl. 292—256)

This invention relates to a latch construction particularly useful in luminaires.

In luminaires it is a customary practice to provide a stationary housing assembly provided with a reflecting means and a hinged globe assembly which is pivoted or hinged at one end and latched at the other end to the stationary housing assembly.

The luminaires are customarily mounted out of doors and are subjected to rain, sleet, and snow and also are usually mounted at considerable elevation so that it is necessary for an attendant to stand on a platform or ladder and reach upwardly to the globe assembly for cleaning, replacing or repair.

Objects of this invention are to provide a latch construction which is highly effective in securely locking the globe assembly to the stationary housing assembly and which has the desirable feature of securely pressing the globe assembly against the housing assembly to thus effectively seal or secure the two assemblies together to prevent the entrance of rain, snow, dust or dirt.

Further objects are to provide a latch construction particularly suitable for luminaires which is so made that the main body portion of the latch provides an effective sleet housing which protects the internally located mechanism of the latch.

A further important feature of this invention is to so construct the latch that a spring pressed latch element or latch proper is provided for yieldingly urging the globe assembly into sealing engagement with the housing assembly and to so associate this latch element and the main body of the latch that in closing the globe assembly the latch element is not contacted by any portion of the globe assembly and thus is not subjected to wear or damage during the closing motion of the globe assembly, in which the latch body portion is moved outwardly by cam means without contacting the latch element or latch proper, and in which when latching occurs the latch element is released and allowed to force the globe assembly into sealing relation with the stationary housing assembly.

In the preferred form of the invention a single spring means is employed and serves not only to rock the latch assembly into latching relation to the globe assembly, but also it urges the latch element into latching position.

Embodiments of the invention are shown in the accompanying drawings in which:

Figure 1 is a fragmentary view of the luminaire showing the latch construction and showing the globe assembly in closed position.

Figure 2 is a fragmentary sectional view through the latch showing the parts in closed position.

Figure 3 is a view similar to Figure 2 showing the latch in released or unlatched position and showing the globe assembly in partially open position.

Figure 4 is a bottom view of the construction shown in Figure 2.

Figure 5 is a sectional view on the line 5—5 of Figure 2.

Figure 6 is a view of a further form of the invention.

Figure 7 is a fragmentary sectional view through the

2

latch of Figure 6 showing the parts in latching position.

Figure 8 is a view corresponding to Figure 7 showing the latch released and showing the globe assembly in partially open position.

5 Figure 9 is a view looking from the right of Figure 7 with parts broken away and parts in section.

Figure 10 is a bottom view of Figure 7.

Referring to the drawings particularly Figures 1 through 5 it will be seen that a luminaire has been shown. This 10 luminaire comprises a stationary housing assembly indicated generally by the reference character 1 and a globe assembly indicated generally by the reference character 2. This globe assembly is pivoted as indicated at 3 to the housing assembly.

15 The globe assembly comprises a globe 4 of light transmitting material which is supported by means of the supporting ring 5, a suitable gasket 6 being interposed between the ring 5 and the globe 4. The ring 5 is provided with trunnions 7 which are supported by hook-like members 8 carried by the body portion, see Figure 1. The members 7 and 8 constitute the hinge indicated generally at 3.

20 The body portion or stationary housing assembly 1 carries a gasket 9 against which the flange of the globe 4 is tightly pressed as shown by Figure 2 by means of a latch indicated generally by the reference character 10.

25 The latch 10 comprises a hood-like body portion 11 pivoted as indicated at 12 on a projecting portion 13 of the stationary housing assembly 1. The body portion 11 of the latch is provided with a curved manipulating and releasing finger 14 which may be manually engaged directly by the hand of the operator or by means of a stick to rock the body portion outwardly to releasing position as shown in Figure 3. A latch element, or latch 30 proper, indicated generally by the reference character 15, is pivoted by means of a pivot pin 16 carried by the body portion, and a spring 17 is coiled about the pin 16 and operatively interposed between the latch element 15 and the body portion 10 and urges the latch element in a clockwise direction as viewed in Figures 2 and 3. The latch element 15 is roughly of inverted U-shape and is provided with a transversely extended member or portion 18 and with a pair of releasing or manipulating arms 19.

35 It is to be noted that from Figures 2, 3 and 5 that the projecting portion 13 of the stationary housing assembly 1 has a downwardly projecting part or flange 20 which engages the arms 19 when the body portion 10 of the latch construction is rocked from latching position as shown in Figure 2 to releasing position as shown in Figure 3 to thus withdraw the latch element 18 from beneath a projecting coacting member 21 formed integrally with the ring 5 of the globe assembly.

40 The body portion of the latch is provided with downwardly projecting fingers or cam like members 22 which coact with the cams or lugs 23 integral with, and forming a part of, the ring 5 when the globe assembly is rocked upwardly.

45 By means of the peculiar construction and coaction of the parts, damage to the latching element or rapid wear thereof is avoided as the latching element 18 is moved out of the way of the lugs 21 when the members 22 of the body portion engage the lugs 23 of the ring 5 during closing motion of the globe assembly and when closing motion is completed, the element 18 moves into position below the lugs 21. Also it is to be noted that when the latch is manually released that the coaction of the portion 20 and the arms 19 also withdraws the latching element from beneath the member 21.

50 Attention is directed to Figures 2 and 3. It will be seen that when the latching bar or member 18 engages the under side of the cam or lug 21 that an upward pres-

sure is transmitted to the globe assembly to force the globe assembly into tightly sealing relation with the stationary housing assembly. Further, there is a reaction produced between the lug 21 and the latch 15 which tends to rock the pin or pivot point 16 of the housing 11 of the latch to its lowest position directly below the pivot point or pin 12. This reactive force thus tends to rock the latch 10 in a clock-wise direction as viewed in Figure 2, that is to say, towards latching position.

In the form of the invention shown in Figures 6 through 10 the same general construction is followed as that previously described with the exception that the body portion 11' of the latch is provided with an additional spring 24 which bears against a projecting member 29' of the stationary housing assembly 1' and urges the body portion 11' in a clock-wise direction.

The primary difference between the construction shown in Figures 1 through 5 for the first form of the invention and Figures 6 through 10 for the second form of the invention is that in the first form the single spring 17 provides the means for producing both of the forces, one of which urges the globe assembly into sealing relation with the stationary housing assembly, and the other of which urges the latch towards latching position, whereas in the second form of the invention an additional spring 24 is employed for urging the latch in assembly 10' towards latching position.

Corresponding parts in Figures 6 through 10 are indicated by the same reference characters as in the first form of the invention except that these reference characters have been primed.

If desired, a manipulating lip or member corresponding to that indicated at 14 in the first form of the invention may be added to the body portion 11' of the latch shown in the second form of the invention.

It is to be understood that the latch is provided with a latching portion in each instance, that is to say, the latch 18 or 18' of the two forms is provided, in each instance, with a latching portion. This latching portion is the actual surface of the member 18 or 18' which engages the bottom side of the lug 21 or 21', respectively. It is to be noted particularly that this latching portion as defined hereinabove is between the two pivots that is to say, in the first form of the invention between the pivots 12 and 16 and in the second form of the invention, between the pivots 12' and 16'.

The two members, forming the latch proper, have a toggle action since the latching portion as explained hereinabove is located between the two pivots and thus squeezes the two main members of the assembly together and produces the sealing action.

It will be seen that very simple types of latch constructions have been shown which are easily operated and fully protected from sleet, rain etc. Further, the latch assembly has very few parts and these parts may be easily produced and assembled.

Although this invention has been described in considerable detail, it is to be understood that such description is intended as illustrative rather than limiting, as the invention may be variously embodied and is to be interpreted as claimed.

I claim:

1. In a latch construction, a first member and a second member, a latch having a main body portion pivoted on said first member, a latch element carried by said body portion and pivoted on said body portion for forming with said body portion a toggle and having a toggle action with said body portion for latching said first and second members in sealing relation, and spring means between said latch element and said body portion for urging said latch element against said second member to thereby impart a thrust to said second member and urge said second member into sealing engagement with said first member, and means carried by said latch element for engaging said first member to rock said latch ele-

ment to releasing position when said body portion is rocked outwardly.

2. In a latch construction, a first member and a second member, a latch having a main body portion pivoted on said first member, a latch element carried by said body portion and pivoted on said body portion for forming with said body portion a toggle and having a toggle action with said body portion for latching said first and second members in sealing relation, the pivot point of said latch element being below and laterally displaced from the pivot point of the body portion, and spring means between said latch element and said body portion for urging said latch element against said second member for moving said second member against said first member and for rocking said body portion inwardly to position a part thereof beneath said first member.

3. In a latch construction, a first member and a second member, a latch having a body portion pivoted on said first member, a latch element pivoted on said body portion and urging said second member against said first member, said latch element having its latching portion located between planes passing through the two pivots, said latch element being pivoted on said body portion at a point below and spaced laterally from the pivot point of said body portion, spring means between said latch element and said body portion for urging said latch element against said second member for moving said second member into sealing engagement with said first member and for urging said body portion inwardly towards said second member.

4. In a latch construction, a first member and a second member, a latch having a body portion pivoted on said first member, a latch element pivoted on said body portion at a point below and spaced laterally from the pivot point of said body portion, spring means between said latch element and said body portion for urging said latch element against said second member for moving said second member into sealing engagement with said first member and for urging said body portion inwardly towards said second member.

5. In a latch construction, a first member and a second member, a latch having a body portion pivoted on said first member, a latch element pivoted on said body portion and urging said second member against said first member, said latch element being pivoted on said body portion at a point below and spaced laterally from the pivot point of said body portion, said latch element having its latching portion located between planes passing through the two pivots, spring means between said latch element and said body portion for urging said latch element against said second member and for urging said body portion inwardly towards said second member, and means carried by said second member and coacting means carried by said body portion for rocking said body portion outwardly when said second member is moved towards said first member, and latch element displacing means carried by said first member and operatively engaging said latch element for rocking said latch element into unlatching position when said body portion is rocked outwardly from said first member.

6. In a latch construction, a first member and a second member, a latch having a body portion pivoted on said first member, a latch element pivoted on said body portion and urging said second member against said first member, said latch element having its latching portion located between planes passing through the two pivots, said latch element being pivoted on said body portion at

a point below and spaced laterally from the pivot point of said body portion, spring means between said latch element and said body portion for urging said latch element against said second member and for urging said body portion inwardly towards said second member, said body portion being of hood-like construction and housing said latch element and said spring means.

7. In a latch construction, a first member and a second member, a body portion pivoted on said first member, a latch element pivoted on said body portion and urging said second member against said first member, said latch element having its latching portion located between planes passing through the two pivots, said latch element being pivoted on said body portion at a point below the pivot point of said body portion, spring means between said

latch element and said body portion for urging said latch element against said second member to move said second member into sealing engagement with said first member, and a second spring means between said first member and said body portion for rocking said body portion inwardly towards said first member.
